UNITED STATES PATENT OFFICE.

FRANK DALKNER, OF ALLENTOWN, PENNSYLVANIA.

COAT.

Application filed March 23, 1926. Serial No. 96,686.

This invention relates to improvements in coat construction and more particularly to the construction of sleeves in coats.

A particular object of the invention is the construction of a coat in which the sleeve will be joined to the coat in such a fashion that the arm movements of the wearer will be hampered as little as possible, so that the coat will fit comfortably and also so that there will be a minimum of wear and distortion upon a portion of the coat which is usually subject to a great deal of strain and wear. This particular improvement in coats is particularly adapted for golf coats and other athletic garments, but is also useful and applicable to coats of the conventional type.

Further objects of the invention will be apparent from the specification and drawings in which—

Fig. 1 is a perspective view of a coat with my improved sleeve, this view being from the outside and a portion of the improvement being indicated in dotted lines.

Fig. 2 is a perspective view of the lining of the coat which is made separate and which is provided with elastic members A as shown in the drawings.

Fig. 3 is an inside perspective view of my improved sleeve.

Fig. 4 is a sectional view along the line 4—4 of Fig. 3.

Fig. 5 is a perspective view of the inside of the sleeve, but showing the extensible pocket attached to the sleeve hole which is a feature of my invention, in this view the extensible pocket being ironed downward in a fixed position.

Fig. 6 is a sectional view along the line 6—6 of Fig. 5.

Fig. 7 is an enlarged section of the connecting members also shown in Fig. 6.

B indicates a normal sleeve attached to the coat on the outside by the row of stitching C. This row of stitching C is the normal line of stitching on the upper part of the sleeve, but where it approaches the under part of the sleeve, then provision must be made to take up the strain on the sleeve when the arm is upraised or in action. For this reason I form on the underside of the sleeve, an extensible pocket D which is shown in dotted lines in Fig. 1 and which is more clearly shown in Figs. 3 and 5. This

55 pocket consists of an extra fold of material as shown in Fig. 3 which is sewn along its upper edge with the line of stitching E, one part of the fold being attached to the sleeve hole by the line of stitching F, sewn over a tape of the conventional style now used in all sleeves. This tape is designated as F.

It will be observed that the only point of attachment for the sleeve itself to the arm hole on the underside is along the lower line of stitches F so that the extensible 60 pocket D which is formed from two parallel folds of material, will give considerable play to the sleeve when stretched. As shown in Fig. 5, after the pocket D is sewed, it is ironed downward into position as shown in

65 Fig. 5. To keep the sleeve in normal position, I employ the lining shown in Fig. 2 having the elastic strips A which are attached to the pocket D at the point G as shown in Fig. 5 and as also shown in Fig.

70 7. The ends of the elastic strips A are sewn to the member H which tends to keep the lining and back of the coat in position at all times. The body of the coat is indicated as K.

75 In this fashion a sleeve construction is produced which will give the utmost play to the sleeve with a minimum of wear. When the arm is in the downward position, it is impossible to notice any differences between this sleeve and the ordinary sleeve and when it is in an upward position, there is the extensible pocket or fold formed in the lower part of the sleeve which comes into play, but does not present any unusual 80 features to the outside view.

85 Having fully described my invention, what I claim is:

1. In a coat, a body portion, a sleeve, said sleeve being attached to the arm-hole 95 by a normal line of stitching on the upper portion of said sleeve, an extensible fold attached to the lower part of the arm-hole of said sleeve and elastic members attached to said fold tending to keep same in a contracted position, said elastic members crossing each other at the back and each having its end attached to the side of the coat opposite the fold to which its other end is attached.

100 2. In a coat, a body portion, a sleeve, said sleeve being attached to the arm-hole by a normal line of stitching on the upper por-

tion of said sleeve, an extensible fold attached to the lower part of the arm-hole of said sleeve and elastic members attached to said fold tending to keep same in a contracted position, said elastic members crossing each other at the back and each having its end attached to the side of the coat op-

posite the fold to which its other end is attached and connecting means joining said elastic members to each other.

In testimony whereof I affix my signature.

FRANK DALKNER.
